Specification for Design.

Patented Sept. 14, 1920.

Application filed December 16, 1919. Serial No. 345,400. Term of patent 14 years.

To all whom it may concern:

Be it known that we, ARMITAGE S. C. FORBES and HARRY E. R. P. FORBES, both citizens of the United States, residing at the city of Los Angeles, county of Los Angeles, State of California, have invented a new, original, and ornamental Design for Table-Bells, of which the following is a specification, reference being had to the accompanying drawing, forming a part thereof.

The figure is an isometric view of a table bell, showing our new design.

We claim;

The ornamental design for a table bell, as shown.

In witness that we claim the foregoing we have hereunto subscribed our names this first day of December, 1919.

ARMITAGE S. C. FORBES.
